UNITED STATES PATENT OFFICE

2,664,186

NONINTERMITTENT LAMP BASE FEEDING
MECHANISMJames Bain, Jr., Waldoboro, Maine, assignor to
General Electric Company, a corporation of
New York

Application December 22, 1950, Serial No. 202,353

10 Claims. (Cl. 198—33)

1

This invention relates generally to automatic product feeding mechanisms, particularly as applied to lamp making machinery and to equipment for supplying or feeding lamp parts to such machinery. Specifically, the invention is concerned with a mechanism for feeding lamp bases to base holders carried at a constant velocity on an endless roller chain employed in a lamp making machine applying the principles of nonintermittent or continuous action.

Most of the lamp making machinery which has been developed up to the present time is of the indexing type wherein the manufacturing operations are performed upon the lamps at spaced work stations fixed in position. The lamp is advanced or indexed from one position to the next by means of suitable conveyor systems which operate in a series of intermittent or discontinuous steps. Since the product must necessarily be temporarily stopped and located at the work station while the manufacturing operation takes place, it necessarily follows that the operating speed of such indexing machinery is limited.

In my copending application No. 202,351, filed December 22, 1950, entitled "Nonintermittent Lamp Base Filling Machine" and assigned to the same assignee as the present application, I have described and claimed a machine applying the principles of nonintermittent or continuous action to the operation of filling a lamp base with cement paste. The present invention is related to it and is specifically concerned with a mechanism for feeding lamp bases to the base holders carried by the roller chain described in that application.

An object of the present invention is the provision of an automatic feeding mechanism for supplying similar products, such as lamp bases, to suitable holders carried at a constant uninterrupted velocity on a roller chain.

Another object of the invention is to provide apparatus for feeding lamp bases with even distribution and in a positive predetermined alignment to a plurality of metering units and suitable for use in conjunction with the feeding of bases in a nonintermittent continuous action machine.

Yet another object of the invention is the provision of apparatus for positively orienting and aligning lamp bases supplied in random alignment from a loading unit.

Other objects of the invention are the provision of specialized equipment and apparatus which may be utilized in conjunction with a mechanism for feeding hollow cylindrical lamp

2

bases in a nonintermittent or continuous fashion to base holders carried on a roller chain.

For further objects and advantages and for a better understanding of the invention, attention is now directed to the following description and accompanying drawings. The features of the invention believed to be novel will be more particularly pointed out in the appended claims.

In the drawings:

10 Fig. 1 is a cross-sectional view of a screw base for a lamp, representative of a type produced in large quantities by the lamp making industry, and suitable for continuous nonintermittent feeding by the mechanism of the present invention.

15 Fig. 2 is a simplified mechanical schematic diagram illustrating the overall functioning of a roller chain and sprocket type nonintermittent base filling machine as described and claimed in my afore-mentioned copending application and making use of the feeding mechanism of the present invention.

20 Figs. 3a and 3b are front elevation views of a base holder carried by the roller chain in the present invention. The two views show the details of the base holder in the locked and unlocked positions, respectively.

25 Fig. 4 is a plan view of the lamp base feeding mechanism embodying the present invention and constituting a portion of the complete lamp base filling machine described in the afore-mentioned copending application. The view is taken along the section line IV—IV with respect to Fig. 5.

30 Fig. 5 is a cross-sectional elevation view of the lamp base feeding mechanism taken along the section line V—V with reference to Fig. 4.

35 Figs. 6a and 6b are side elevation and sectional views respectively of one of the slides for feeding the bases and illustrating certain features described in the specification.

40 While the present invention may be utilized for feeding lamp bases or similar products to suitable holders carried by a roller chain in connection with other continuous nonintermittent manufacturing processes, the preferred embodiment which 45 will be described in detail herein is specifically designed to operate in conjunction with the non-intermittent lamp base filling machine described in my copending application. Accordingly, the product and the operation desired to be performed thereon, which are fully described in the copending application, will be summarized briefly herein in order to facilitate an understanding of the purpose and function of the feeding mechanism.

50 55 The lamp base filling machine of the copending

application may be utilized to insert basing cement into cylindrical bases commonly utilized in the lamp making industry. A typical base is illustrated at 1 in Fig. 1. It is of the miniature screw or Edison type and comprises a thin-walled threaded hollow cylindrical metal shell 2 which is usually made of brass but which may also be made of aluminum or other suitable metal. The shell is slightly outwardly flared at 3 in order to receive a glass bulb for constituting a finished lamp, and has an opening at its outer end which is closed by a web 4 of plastic insulating material such as glass or a thermosetting phenolic type of plastic. Mounted on a boss 5 at the outer end of the web 4 is a contact eyelet 6 which provides one terminal of the lamp, the other terminal being provided by the base shell itself. The plastic web 4 has a hole or perforation through its center for passing a lead wire therethrough and making connection to the contact eyelet 6 in order to effect a circuit to the filament located in the bulb to which the base will be attached. The cross hatched area 7 represents cement paste annularly disposed within the periphery of the base shell for securely fixing the glass bulb to the base in the finished product constituting an electric lamp.

The specific purpose of the nonintermittent lamp base filling machine considered in the copending application is to receive the bases, as illustrated in Fig. 1 less the cement, and to dispose an annular ring of cement within it as shown. The specific purpose of the lamp base feeding mechanism described in the present application is to feed empty bases, that is bases not containing the ring 7 of cement paste, in predetermined alignment to the base holders carried on the roller chain utilized in the copending application.

The lamp base filling machine described in the copending application automatically inserts the cement paste into the bases carried by the holders on the roller chain as they proceed with constant uninterrupted velocity on their course through the machine, and it may achieve a production rate of 40,000 bases per hour. By comparison, the production rate of intermittent or indexing machinery such as is provided by the prior art for filling lamp bases with cement, is approximately 4,000 bases per hour. It will thus be realized that the lamp base filling machine described in the copending application permits a remarkable increase in production. The specific problem which the mechanism embodying the present invention is designed to solve is that of feeding with positive alignment 40,000 bases per hour to base holders carried on a roller chain at a constant velocity past a feeding station, the feeding station being, in effect, a sprocket around which the chain is wrapped over a predetermined angle.

Referring to Fig. 2, a preferred arrangement of a complete lamp base filling machine embodying the base feeding mechanism of the present invention, along with the cement injecting apparatus of the copending application, may be understood by reference to the simplified schematic diagram illustrated therein. The arrangement comprises an articulated conveyor such as a roller chain 10 on which are mounted suitable holders for retaining the product, that is, the lamp bases such as illustrated in Fig. 1. The chain is wrapped around and engages the teeth of a number of sprockets of which the major sprockets 11 and 12 are of a larger size. These

two major sprockets support the mechanical operators performing respectively the functions of feeding the bases to the holders carried by the chain, and of filling the bases with cement. The chain is arranged to be driven in such fashion that it moves directly from the feeding sprocket 11 to the cement filling sprocket 12, as indicated by the arrows. After leaving the filling sprocket, the chain passes around a driving or power input sprocket 13, and then a sprocket 14 which operates as a chute through which the lamps drop after being blown out of the holders by means of air nozzles mounted on an ejector sprocket 15. Sprocket 13 serves to keep the roller chain and associated mechanisms in movement and power may be supplied to it by any suitable means, such as, for instance, the input shaft of a worm gear reducer driven by a variable speed electric motor. The chute sprocket 14 is also adapted to exert a tension on the chain by means of a sliding mount and the spring 16 so that the chain may be kept taut at all times and sagging prevented. The figure also shows a fire bank at 17 and various cam tracks at 18 and 19, of which the latter will be considered in the present application.

Where the filling mechanism is designed to operate at a production rate of 40,000 bases per hour, the feeding mechanism must supply the same number of bases per hour to the holders on the chain. For the above-mentioned production rate, or more accurately, for a production of 43,200 bases per hour, twelve bases must be supplied per second and aligned in a definite arrangement so that they may be properly received and held by the base holders.

Referring to Fig. 3a, a suitable base holder 20 is shown in the locked or closed position, that is, in the position for positively holding a lamp base. The holder comprises an L-shaped frame member 21 and a pair of curved jaws 22 and 23 pivotally mounted for swivelling in a vertical plane. The jaws have intermeshing teeth portions at their lower ends which cause them to swivel oppositely to equal extents during actuation. One of the jaws, namely 22 in the drawing, is extended past the pivot point into a bell crank 24 for the purpose of operating the jaws. The bell crank has a roller 25 mounted at its end and adapted to bear against a suitable cam surface, such as the cam tracks 18 and 19 in Fig. 2.

The horizontal angle of the frame member 23 is secured in suitable fashion to a link in the chain, as by extensions of adjoining roller pins through the mounting holes 26. The base holder 20 is thus supported on the roller chain 10 in such fashion that the jaws pivot in a plane normal to the plane of the sprocket 12. A helical spring 27 exerts a tension between corresponding points on opposite jaws and holds them closed normally for securely gripping the lamp bases. The bases may be released from the jaws by operating the bell crank 24 by providing a suitable cam surface for engaging the roller 25. The jaws are shown in their open or unlocked position in Fig. 3b, wherein it will be understood that, through the operation of the interlocking spur teeth at the bottom of the jaws, a symmetrical opening of the jaws is achieved even though the bell crank 24 operates on one of the jaws only.

Referring to Fig. 4, the chain 10 engages the major sprocket 11 and causes it to rotate at a rate of one revolution per second in a counter-clockwise direction as indicated by the arrows. The chain comprises a series of links 30 and rollers 31 joined together in conventional fashion.

It will be understood that other known types of articulated conveyors may be used instead of that which has been illustrated. Mounted on the chain 10 and spaced in such fashion that, during the period of wrap of the chain around the sprocket, they assume 30° intervals, are the base holders 20.

The chain is effectively wrapped around the sprocket 11 from the position indicated at 90° on the drawing to the 270° position. During the 10 interval of time consumed by any one particular base holder in revolving through this angular displacement, such base holder has an angular velocity identical to that of the sprocket so that it is to all intents and purposes fixed with respect to the sprocket.

As may be seen in Fig. 5, the sprocket wheel 11 is supported by means of ball bearings 33 on a shaft 34 locked to a bed plate or frame 35 supporting the whole mechanism. The sprocket 11 carries at 30° intervals twelve identical injection units indicated generally at 36 and 36', whose function is to insert the product, in this case the bases, into the base holders. Located immediately above the injection units, are the corresponding metering units 37 and 37', likewise twelve in number, one for each injection unit. The metering units are attached to the radial spokes 38 of a spider 39 which is mounted upon the hub 41 of the sprocket 11 and locked to it by means of the set screw 42. The spider 39 thus revolves with the sprocket and it is additionally supported by the upper ball bearings 43 mounted on the fixed stud 44. Leading radially upwards and inwards from the metering units towards the axis of the spider 39, are twelve V-shaped slides 45 constituting generally the alignment units. Located above the sprocket 11 and the spider 39 is a loading unit indicated generally at 46.

For purposes of description, the feeding mechanism can be divided into four separate units under the following headings which will be considered consecutively:

1. The loading unit
2. The alignment unit
3. The metering unit
4. The injecting unit

The loading unit

The purpose of the loading unit is to transfer the bases without damaging them, from a stationary overhead reservoir to the revolving V-shaped slides or alignment units 45 having a sizable angular velocity. The main components of the loading unit are the overhead hopper 47, the connecting pipe 48 containing an adjustable gate 49 and a rubber rotor 51, and a distributing cup 52 containing twelve flanged or conical openings 53, one for each of the alignment units 45. The overhead hopper 47 may either store the bases in a quantity sufficient for a definite production period, or may be continuously supplied with bases by means of a separate conveyor system. The bases are gravity fed into the connecting pipe 48 and the rate at which they feed through the pipe to the rotor may be regulated by means of the adjustable gate 49. It will, of course, be understood that the overhead hopper and adjustable gate which have been described are a rather elementary system for feeding bases and other more refined systems are available which make use of vibrating feed troughs. The rubber rotor 51 has four blades mounted on a spindle 54 which has a pulley 55 fixed to its

upper end. The pulley 55 is driven by a flexible V-belt 56 passing around a second pulley 57 fixed to a spindle 58 mounted on the hub of the distributing cup 52. The spindle 58 is made fast to the hub of the distributing cup 52 by a set screw 59, and the distributing cup, in turn, is made fast to the hub of the spider 39 by a set screw 61. The spider 39, the distributing cup 52, and the pulley 57 thus all revolve with the sprocket 11. The rubber rotor 51 revolves at three times the angular velocity of the sprocket, and, being provided with four blades, it will sweep twelve bases into the distributing cup for each revolution of the sprocket.

The distributing cup 52 is a thick disc having twelve conical or funnel-shaped openings 53 through its body, as previously mentioned. These openings are positioned immediately above the slides of the corresponding alignment units 45. The bases are swept into the distributing cup in a haphazard fashion by the rotor 51 and distribute themselves at random among the twelve openings in accordance with the law of averages. Although for one single revolution of the sprocket it cannot be expected that each alignment unit will receive a single base from its corresponding opening in the distributing cup, over a number of revolutions each alignment unit will receive the same total number of bases. In addition, the adjustable gate 49 provides a means for regulating the total flow of bases into the distributing cup and achieving a suitable distribution into the alignment units.

The alignment unit

The alignment units consist essentially of the twelve V-shaped slides 45, one of which is shown in sectional elevation and in cross section in Figs. 6a and 6b respectively. The upper ends of the slides are located directly below the corresponding openings in the distributing cup 52 and the lower openings abut against the respective metering units 37. As may be seen in Fig. 4, the V-shaped slides extend radially outward to the alignment units in the fashion of spokes of a wheel. The purpose of the alignment units is to orient the bases into a definite predetermined arrangement for feeding to the injector units by the metering units. The V-shaped slide is very simple in design yet provides a positive orientation to the bases. The positive orientation results from the fact that the base has a center of gravity located nearer to its closed end, that is, to the end provided with the eyelet 6 mounted in the plastic web, as seen in Fig. 1. When the base moves down the inclined slide, the friction encountered in bearing against the walls of the V tends to retard the heavy end of the base more than the light end, so that the base has a tendency to tumble or spin until the lighter or open end is pointing downwards. By suitable choice of the slide material, or more accurately of the coefficient of friction of the slide surface, and with the proper angle of the V and inclination of the slide as a whole, the base will orient itself after a very short travel. All the bases react to the V-shaped slide in the same fashion; namely, all enter the metering units with the open ends of the bases first or facing downwards.

One of the main advantages of a V-shaped slide as an alignment unit is the simplicity of interchangeability. Different sizes of bases may be accommodated by providing slides having a suitable angle in the V. Also the same V-shaped

slides may be used for bases of slightly different sizes, in which case the larger bases ride higher in the V whereas the smaller ones ride lower. The centrifugal force resulting from the angular velocity of the slides will have little effect on the bases riding down the slides, because it is relatively small. In practice, the slides are adjusted so as to just hold the bases without sliding when the machine is stopped. Thereafter as soon as the sprocket begins to revolve, the additional centrifugal force will be just sufficient to cause the bases to slide. It will be understood that the distributing cup 52 deposits only one base at a time on any one slide by reason of the fact that the revolving rubber rotor 51 permits only one base to be fed through at a time.

The metering unit

The mechanism comprises twelve metering units indicated generally at 37 and 37' in Figs. 4 and 5. Each comprises a vertical feed tube 62 affixed to the outer end of the radial spoke 38 projecting from the hub of the spider 39. The upper end of the tube is cut away on the side corresponding to the lower end of the inclined slide 34, and the lower end is located directly over the associated injecting unit 36. Mounted on the outer side of the tube 62 is a vertical lever 63 hinged to the tube at 64 and spring loaded so as to be pivoted outwards by means of a helical spring 65. The lever 63 carries at its lower extremity a transverse arm 66, on the outer end of which is mounted a roller 67 which is adapted to bear against a cam track or surface 68 for actuating the lever. The cam track 68 encircles the periphery of the sprocket from substantially 300° through 0° to 60° as seen in Fig. 4. The transverse arm 66 has an annular portion encircling the tube 62 and carrying at its inner end a pin 69 which projects inwardly into the tube 62 when the lever 63 is unactuated and prevents the bases 1 from falling through the tube. In addition the lever 63 carries a spring loaded plunger 71 which is adapted to penetrate into the tube 62 for engaging the next base above the lowest one held in the tube. Thus, as soon as the lever 63 is actuated by reason of the roller 67 engaging the cam track 68, the lower pin 69 is drawn out from the tube and the lowest base is released while the upper plunger 71 enters the tube and prevents the next base above the lowest one from falling through. The metering unit may be seen in its unactuated position at 37' on the right hand side of the mechanism in Fig. 5, and in its actuated position at 37 on the left hand side of the mechanism. The metering unit thus permits only one base fall through onto the injecting unit during one revolution of the sprocket 12.

The injecting unit

The function of the injecting unit is to convey the product, in this case the lamp base 1, from the metering unit 37 to the base holder 20 carried around the sprocket on the chain. It comprises a member adapted to receive the product in one position and to insert it into the holder in another position. For handling the base 1, the member is a finger type prong 72 having an outer diameter slightly under the inside diameter of the base. The prong 72 is spring pivoted on the end of a radially reciprocable push rod 73 which carries at its inner end a roller 74 adapted to engage a stationary harmonic cam 75 located in a hollow portion of the hub of the

sprocket 11. The harmonic cam is made fast to the shaft 34 by the upper locking nut 76 so that it is held fixed with respect to the bed plate 35. Twelve finger prongs are carried on identical radial rods at 30° intervals around the periphery of the sprocket 11. An endless coiled helical spring 77 holds the rollers 74 tight against the surface of the cam 75.

The base 1 is dropped onto the prong, by the metering unit 37, with its open end down so that it fits over the prong in its upright position. As the sprocket rotates from the 90° to the 180° position, as shown in Fig. 4, the stationary harmonic cam forces the push rod forward until the finger prong is outwardly advanced and tripped into the horizontal or reclined position by a roller cam 78, as seen on the right-hand side of Fig. 5. During the tripping operation of the finger prong, the bases are prevented from falling off the prongs by a curved spring blade 79 supported on the metering unit 37, which blade forcibly holds the base on the prong. The push rod and the finger prong then continue to move forward until, at the 180° position, the base is completely within the base holder 20. The jaws of the base holder have previously been opened by the cam track 19 encircling the sprocket up to the 180° position. The cam track ends at this position, so that the base holder jaws close on the base and lock it in position. As the sprocket continues to revolve, the push rod is retracted radially inward by reason of the shape of the harmonic cam and the tension of the spring 77, so that the finger prong is removed from the base and pivoted up to the loading position, ready for the next operation.

It will be understood that although the invention has been described in considerable detail as to the specific embodiment illustrated in the drawings, various modifications may be made without departing from the invention. Moreover, whereas the invention has been described in connection with a machine for inserting cement into lamp bases, it is not restricted thereto and may be used for feeding bases or similar products into suitable holders carried on a roller chain at a constant uninterrupted velocity, irrespectively of the nature of the operations to be subsequently performed upon the product. The appended claims are therefore intended to cover any such modifications coming within the true spirit and scope of the invention.

What I claim as new and desire to secure by Letters Patent of the United States is:

1. A mechanism for feeding cylindrical articles to holders therefor mounted at equal intervals on an articulated conveyor adapted to move uninterruptedly, comprising a sprocket adapted to engage said conveyor over a predetermined angle of wrap, a cam-actuated injecting unit fast to said sprocket and comprising means receiving said articles in an upright position and delivering them in a substantially horizontal position to said holders during successive ones of said angles, a metering unit fast to said sprocket and supported over said injecting unit and adapted to release one article to it at a time, an alignment unit fast to said sprocket and supported over said metering unit for feeding said articles in fixed orientation to said metering unit, and means for feeding said articles at a controlled rate to said alignment unit.

2. A mechanism for feeding hollow cylindrical articles to holders therefor mounted at equal intervals on an articulated conveyor adapted to

move uninterruptedly, comprising a sprocket adapted to engage and revolve with said conveyor over a predetermined angle of wrap, thereby assuring zero relative motion between them during said angle, a cam-actuated injecting unit fast to said sprocket and comprising a pivotable finger prong receiving said articles in an upright position and delivering them in a substantially horizontal position to said holders during successive ones of said angles, a metering unit supported from said sprocket over said injecting unit and adapted to release one article to said injecting unit per revolution of said sprocket, an alignment unit supported from and revolving with said sprocket for feeding said articles in fixed orientation to said metering unit, and means for feeding said articles at a controlled rate from a reservoir to said revolving alignment unit.

3. A mechanism for feeding hollow cylindrical articles to holders therefor mounted at equal intervals on an articulated conveyor adapted to move uninterruptedly, comprising a sprocket adapted to engage and revolve with said conveyor over a predetermined angle of wrap, thereby assuring zero relative motion between them during said angle, an injecting unit fast to said sprocket and positioned for cooperating with one of said holders during successive ones of said angles, said injecting unit comprising a radially reciprocable push rod and a pivotable member on the outer end thereof adapted to receive said article in an upright position and to insert it into the cooperating holder in a substantially horizontal position, a stationary cam located for actuating said push rod during a revolution of said sprocket and effecting the pivoting of said member, a metering unit supported from said sprocket over said injecting unit and adapted to release one article to said member per revolution of said sprocket, an alignment unit supported from and revolving with said sprocket for feeding said articles in fixed orientation to said metering unit, and means for feeding said articles at a controlled rate from a reservoir to said revolving alignment unit.

4. A mechanism for feeding hollow cylindrical articles having one end lighter than the other to holders therefor mounted at equal intervals on an articulated conveyor adapted to move uninterruptedly, comprising a sprocket adapted to engage and revolve with said conveyor over a predetermined angle of wrap, thereby assuring zero relative motion between them during said angle, a plurality of injecting units mounted on said sprocket and spaced for alignment with successive holders over said angle, each of said injecting units comprising a radially reciprocable push rod and a pivotable member on the outer end thereof adapted to receive said article in an upright position and to insert it into a cooperating holder in a substantially horizontal position, a stationary cam located for actuating said push rods during a revolution of said sprocket and effecting the pivoting of said members, a plurality of product metering units supported from said sprocket over said injecting units, each of said metering units being adapted to release one article to said member of its associated injecting unit per revolution of said sprocket, a plurality of revolving alignment units supported from said sprocket for feeding said articles lighter end down to said metering units, each of said alignment units including a V-shaped slide inclined radially downwards from the axis of said sprocket to the associated metering unit, and means for feeding

said articles at a controlled rate from a reservoir to the axial ends of said slides.

5. A mechanism for feeding hollow cylindrical lamp bases to holders therefor mounted at equal intervals on a roller chain adapted to move at constant uninterrupted velocity, comprising a sprocket adapted to engage said chain over a predetermined angle of wrap, a cam-actuated injecting unit mounted on said sprocket and comprising means receiving said bases in an upright position and delivering them in a substantially horizontal position to said holders during successive ones of said angles, a base metering unit supported from said sprocket over said injecting unit and adapted to release one base to said injecting unit per revolution of said sprocket, an alignment unit supported from and revolving with said sprocket for feeding said bases in fixed orientation to said metering unit, and means for feeding said bases at a controlled rate to said revolving alignment unit.

6. A mechanism for feeding hollow cylindrical lamp bases to holders therefor mounted at equal intervals on a roller chain adapted to move at constant uninterrupted velocity, comprising a sprocket adapted to engage said chain over a predetermined angle of wrap, an injecting unit mounted on said sprocket and positioned for alignment with one of said holders during successive ones of said angles, said injecting unit comprising a radially reciprocable push rod and a pivotable finger prong mounted on the outer end thereof and adapted to receive a base while pivoted into an upright position and to insert it into a cooperating holder while pivoted into a reclined outwardly advanced position, a stationary cam located for actuating said push rod during a revolution of said sprocket, thereby to operate said finger prong from said upright to said reclined position, a base metering unit supported from said sprocket over said injecting unit and adapted to release one base to said prong for each operation thereof into its upright position, an alignment unit supported from and revolving with said sprocket for feeding said bases in fixed orientation to said metering unit, and means for feeding said bases at a controlled rate to said revolving alignment unit.

7. A mechanism for feeding hollow cylindrical lamp bases to holders therefor mounted at equal intervals on a roller chain adapted to move at constant uninterrupted velocity, comprising a sprocket adapted to engage said chain over a predetermined angle of wrap, a plurality of injecting units mounted on said sprocket and spaced for alignment with successive ones of said holders over said angles, each of said injecting units comprising a radially reciprocable push rod and a pivotable finger prong mounted on the outer end thereof and adapted to receive a base while pivoted into an upright position and to insert it into a cooperating holder while pivoted into a reclined outwardly advanced position, a stationary cam located for reciprocating said push rods during a revolution of said sprocket, thereby to actuate said prongs from their upright to their reclined position, a plurality of base metering units supported from said sprocket over respective ones of said injecting units, each of said metering units being adapted to release one base to the prong of its associated injecting unit for each actuation thereof into its upright position, a plurality of revolving alignment units supported from said sprocket for feeding said bases in fixed orientation to said metering units, and

means for feeding said bases at a controlled rate to said revolving alignment units.

8. A mechanism for feeding hollow cylindrical lamp bases having one end lighter than the other to holders therefor mounted at equal intervals on a roller chain adapted to move at constant uninterrupted velocity, comprising a sprocket adapted to engage said chain over a predetermined angle of wrap, a plurality of injecting units mounted on said sprocket and spaced for alignment with successive ones of said holders over said angles, each of said injecting units comprising a radially reciprocable push rod and a pivotable finger prong mounted on the outer end thereof and adapted to receive a base while pivoted into an upright position and to insert it into a cooperating holder while pivoted into a reclined outwardly advanced position, a stationary cam located for reciprocating said push rods during a revolution of said sprocket, thereby to actuate said prongs from their upright to their reclined position, a plurality of base metering units supported from said sprocket over respective ones of said injecting units, each of said metering units being adapted to release one base to the prong of its associated injecting unit for each actuation thereof into its upright position, a plurality of revolving alignment units supported from said sprocket for feeding said bases in fixed orientation to said metering units, each of said alignment units including a V-shaped slide inclined radially downwards from the axis of said sprocket to a cooperating metering unit for feeding said bases lighter end down, a revolving distributing cup fast to said sprocket and having vertical openings therethrough adapted to distribute bases at random to the axial ends of said slides, and means for feeding said bases at a controlled rate to the axial ends of said slides.

9. A mechanism for feeding hollow cylindrical lamp bases having one end lighter than the other to holders therefor mounted at equal intervals on a roller chain adapted to move at constant uninterrupted velocity, comprising a sprocket adapted to engage said chain over a predetermined angle of wrap, a plurality of injecting units mounted on said sprocket and spaced for alignment with successive ones of said holders over said angles, each of said injecting units comprising a radially reciprocable push rod and a pivotable finger prong mounted on the outer end thereof and adapted to receive a base while pivoted into an upright position and to insert it into a cooperating holder while pivoted into a reclined outwardly advanced position, a stationary cam located for reciprocating said push rods during a revolution of said sprocket, thereby to actuate said prongs from their upright to their reclined position, a plurality of base metering units sup-

ported from said sprocket over respective ones of said injecting units, each of said metering units being adapted to release one base to the prong of its associated injecting unit for each actuation thereof into its upright position, a plurality of revolving alignment units supported from said sprocket for feeding said bases in fixed orientation to said metering units, each of said alignment units including a V-shaped slide inclined radially downwards from the axis of said sprocket to a cooperating metering unit for feeding said bases lighter end down, a revolving distributing cup fast to said sprocket and having vertical openings therethrough adapted to distribute bases at random to the axial ends of said slides, and means for feeding said bases at a controlled rate from a reservoir to said cup.

10. A mechanism for inserting hollow cylindrical lamp bases having one end lighter than the other into holders carried at constant uninterrupted velocity on a chain, comprising a sprocket adapted to engage said chain over a predetermined angle of wrap, a channel, means for feeding said bases one at a time into said channel, a distributing cup located below said channel and adapted to rotate with said sprocket, said distributing cup having a plurality of openings therethrough each adapted to receive said bases at random but in equal numbers when averaged over a period of time, a plurality of alignment units each comprising an inclined V-shaped slide supported from said sprocket with its upper end located below an opening in said distributing cup and feeding said bases lighter end down, a plurality of metering units supported from said sprocket at the outer ends of said V-shaped slides, said metering units comprising a tube for accumulating a reserve of said bases, and means for allowing one of said bases to fall through during one revolution of said sprocket, and a plurality of injector units mounted on said sprocket and each comprising pivotable means receiving said bases in an upright position and delivering them in a substantially horizontal position to said holders during successive ones of said angles.
